(57) **CLAIM**

The ornamental design for a solid state light source display
case lamp, as shown and described.

DESCRIPTION

FIG. 1 is a perspective view of an embodiment of the ornamental
design of a solid state light source display case lamp
including an interconnect between two distinctive solid state
light source display case lamps.

FIG. 2 is a top view of an embodiment of the ornamental
design of the solid state light source display case lamp includ-
ing an interconnect between two distinctive solid state light
source display case lamps.

FIG. 3 is a side view of an embodiment of the ornamental
design of the solid state light source display case lamp includ-
ing an interconnect between two distinctive solid state light
source display case lamps.

FIG. 4 is a bottom view of an embodiment of the ornamental
design of the solid state light source display case lamp includ-
ing an interconnect between two distinctive solid state light
source display case lamps; and,

FIG. 5 is an end view of an embodiment of the ornamental
design of the solid state light source display case lamp includ-
ing an interconnect between two distinctive solid state light
source display case lamps.
